UNITED STATES PATENT OFFICE.

HENRY KLEIN, OF CLEVELAND, OHIO.

ADJUSTABLE WAISTBAND.

1,185,914.

Specification of Letters Patent.

Patented June 6, 1916.

Application filed July 9, 1915. Serial No. 38,971.

To all whom it may concern:

Be it known that I, HENRY KLEIN, a citizen of the United States, residing at Cleveland, in the county of Cuyahoga and State of Ohio, have invented a new and useful Adjustable Waistband, of which the following is a specification.

This invention relates to an improvement in an adjustment for waist bands and is applicable more particularly to waist bands of trousers.

The object of the invention is to provide means whereby the waist band may be adjusted so that it will fit the waist of the wearer without presenting any wrinkles, which are so prevalent with the attachments generally provided for tightening the waist band of a garment.

A further object of the invention is in mounting the adjusting means so that it is unobservable from the exterior surface of the waist band, but which, at the same time, is accessible for taking up or letting out the waist band as the occasion may demand.

The invention consists of certain novel features of construction and combinations of parts which will be hereinafter described and pointed out in the claims.

It will be evident that changes in the form, proportion, material and minor details of construction within the scope of the appended claims, may be made without departing from the spirit or sacrificing any of the advantages of this invention.

In the accompanying drawing, Figure 1 is a view in elevation showing a portion of the garment and waist band. Fig. 2 is a view in elevation of the inner surface of the waist band. Fig. 3 is a view showing the interior construction of the waist band with the lining broken away. Fig. 4 is a perspective view from the inner surface of the waist band showing a slightly modified form, and Fig. 5 is a perspective view with a portion of the waist band broken away to disclose the interior construction of the form shown in Fig. 4.

A represents the garment which is provided with the usual waist band at the upper edge thereof, as indicated at 1, the upper edge of the garment being turned inwardly, as at 2, and connected to the inner surface of the garment is a belting or facing 3 of canvas or the like.

The waist band 1 of the garment and the belting or facing 3 are provided with a

V-shaped opening or notch 4, the edges of the waist band and belting along the opening being connected together by suitable stitching 5. A lining or apron lining 6 is connected to the inner surface of the waist band and is connected at its upper edge to the inturned edge 2 of the waist band 1 by suitable stitching. A belt or tunnel loop 7 is connected to the lining 6 along the upper portion and on the inner surface of the lining by stitching 8. The tunnel loop 7 extends over the upper edge of the waist band and downwardly over the V-shaped opening or notch 4, for forming a closure for the notch. The lower edges of the belt or tunnel loop, the belting or facing 3, and the lining 6, are all connected together by suitable stitching 9. The stitching, which fastens the upper edge of the lining to the upper edge of the waist band, does not extend to the V-shaped opening 4 but considerable space is afforded between the end of the stitching and the edges of the belt or tunnel loop 7, as indicated at 10. By forming these openings or spaces 10 between the upper edges of the garment A, lining 6 and the vertical edges of the tunnel loop 7, the edges of the V-shaped opening or notch can be drawn together for reducing the size of the opening or notch 4, and at the same time drawing the unstitched portion of the waist band adjacent to the tunnel loop into the tunnel loop, thereby reducing the size of the waist band without producing any perceptible wrinkle or pucker in the garment. The edges of the notch 4 are drawn together or allowed to be separated by means of a tape or strap 11, of any suitable material, which is connected along one edge of the opening 4, as at 12, by suitable stitching. This tape then passes across the opening and through the metal loop 13 which is fastened to the waist band along the opposite edge of the opening. The tape after passing through the loop is again drawn across the V-shaped opening and through a slot 14 formed in the lining 6, and is connected to a buckle 15 which is connected to the waist band of the garment on the outer surface 100 of the lining 6.

In the modified form shown in Figs. 4 and 5, a gusset or gore 16 is connected to the waist band for covering the V-shaped opening 4. The gusset or gore is preferably applied to the inner surface of the belting or facing 3. A tape 17 is connected to the

waist band, along one edge of the opening 4, and extends across the opening and gusset 16, and is provided at its outer terminal with a plurality of resilient studs 18 which 5 are adapted to be sprung into a socket 19 connected to the waist band on the opposite side of the opening. The lining 6 in this form is not connected along its lower edge by means of stitching to the facing or belt- 10 ing 3 and to the garment A, but is fastened by means of sockets 20 connected to the facing 3, and resilient heads 21 connected to the inner surface of the lining, whereby the heads 21 can be sprung into the sockets 20 15 for fastening the lining to the waist band or garment A. The gusset or gore 16 is employed in this instance more particularly to prevent the tape from passing through the opening 4 and between the tunnel loop and 20 the waist band if for any reason it should become disengaged from the socket 19.

The construction set forth in Figs. 4 and 5 is similar in other respects to the construction set forth in Figs. 1, 2 and 3, and the 25 same adjustments can be obtained by both. Of course when it is desired to make an adjustment or use the construction set forth in Figs. 4 and 5, the lining 6 must first be released from the waist band so that access 30 can be had to the tape 17, whereas in the construction set forth in Figs. 1, 2 and 3, the tape 11 can be grasped by inserting the hand along the inner side of the waist band.

From the foregoing it will be seen that 35 any number of these V-shaped openings 4 may be formed in the waist band of a garment for the purpose of taking up or letting out the waist band to suit the waist of the wearer of the garment. The openings will 40 all be concealed by the tunnel loops 7, which are and may be employed as belt loops for supporting the garment.

What is claimed is,—

1. In a garment, a waist band having a 45 V-shaped opening formed therein, a belt or tunnel loop connected to the outside of the waist band below the opening, and extending over the upper edge of the waist band and connected to the inner side thereof and 50 completely covering said opening, and means connected to and arranged on the inside of the waist band for drawing the edges of the opening together and into the belt or tunnel loop.

55 2. In a garment, a waist band having a V-shaped opening formed therein, a tunnel loop connected to the outside of the waist band below the opening, a lining connected to the upper edge of the waist band and extending along the inner side thereof, the upper terminal of said tunnel loop extending 60 over the upper edge of the waist band and between the inner surfaces of the waist band and lining, said loop being connected to the lining at its upper terminal and com-

pletely covering said opening, and means connected to and arranged on the inside of the waist band for drawing the edges of the opening together.

3. In a garment, a waist band having a 70 V-shaped opening formed therein, a tunnel loop connected to the outside of the waist band below the opening and extending over the upper edge of the waist band for closing the opening, a lining located along the 75 inner surface of the waist band and connected to the upper edge thereof, and to the tunnel loop for fastening the upper terminal of the tunnel loop to the waist band, the upper edge of the waist band being disconnected from the lining for a short distance at each side of the tunnel loop to permit the upper edge of the waist band adjacent to the V-shaped opening to be drawn into the tunnel loop upon the contraction of 80 the V-shaped opening, and means extending across the opening for contracting the latter and reducing the size of the waist band.

4. In a garment, a waist band having a 85 V-shaped opening formed therein, a lining 90 connected to the waist band and located along the inner surface thereof, a tunnel loop connected to the outside of the waist band below the opening and extending over the upper edge of the waist band for closing 95 the opening, the upper terminal of said tunnel loop being received between the waist band and lining and connected to the lining, means on the inner surface of the waist band for contracting the V-shaped opening and 100 reducing the size of the waist band, the upper edge of said waist band adjacent to the V-shaped opening being disengaged from the lining for a short distance inside thereof, whereby said ends may be drawn into the 105 tunnel loop upon the contracting of the opening.

5. In a garment, a waist band having a 110 V-shaped opening, a tunnel loop connected to the outside of the waist band below the opening, and extending over the upper edge of the waist band and completely closing 115 said opening, a lining connected to the inner surface of the waist band and to the upper terminal of the tunnel loop for maintaining the tunnel loop in position over the V-shaped opening, a tape connected to the waist band on one side of the opening, a loop connected to the waist band on the opposite side of the opening through which 120 loop the tape passes, and a buckle connected to the waist band on the opposite side of the opening from the loop to which buckle the tape is connected for holding the waist band in its adjusted position.

6. In a garment, a waist band, a belting or facing connected to the inner surface thereof, said belting and waist band having a V-shaped opening formed therein, a tunnel loop connected to the outside of the waist 130

band below the opening and extending over the upper edge of the waist band for completely closing said opening, a lining connected to the upper edge of the waist band and the upper terminal of the tunnel loop, a tape connected to the inner surface of the waist band at one edge of the opening, a loop connected to the waist band on the opposite edge of the opening through which 10 the tape passes, and a buckle connected to the lining and waist band on the opposite side of the opening from the loop, said lining having an opening therethrough through which the tape passes, said tape extending across the opening from the loop and through the opening of the lining, and connected to the buckle for holding the waist band in its adjusted position, the lower edges 15 of the lining, belting or facing, waist band and tunnel loop all being connected together.

7. In a garment, a waist band having a V-shaped opening formed therein, a tunnel loop provided on the outside of the waist band over said opening, said loop being extended over the waist band for closing said opening, means for securing the upper end of the tunnel loop to the inside of the waist band, a tape secured to the inside of the waist band at one side of the opening and 25 extended across said opening, and means for adjustably securing the free end of the tape to take up or let out the opening in the waist band.

In testimony, that I claim the foregoing 30 as my own, I have hereto affixed my signature in the presence of two witnesses.

HENRY KLEIN.
